UNITED STATES PATENT OFFICE

GEORGE M. SPENCER, OF CHICAGO, ILLINOIS

FLUID CLEANER

Application filed June 18, 1930. Serial No. 461,906.

This invention relates in general to a fluid cleaner and more particularly to a method and apparatus for cleaning fluid such as air, liquids, and the like, or for separating solid particles and the like from fluid.

An important object of the invention is to provide such a device which will separate solid particles from fluid without materially restricting the flow of the fluid.

Another important object of the invention is to provide such a device which will efficiently separate solid particles from fluid without choking or accumulating materials in the operating parts such as may interfere with the operation of the device.

Another important object of the invention is to provide a new, novel and improved method of separating particles from fluid.

Numerous other objects and advantages of the invention will be apparent as it is better understood from the following description, which, taken in connection with the accompanying drawing, discloses a preferred embodiment thereof.

Referring to the drawing:

Figure 1 is a vertical section of a device embodying my invention. Movement of fluid through the device being indicated by arrows, and,

Fig. 2 is a sectional view taken substantially on line 2-2, in Figure 1, and showing details of construction.

To illustrate the invention I have shown a housing or body 11, formed of a central part 12, a cover part 13, and a bottom closure or cover 14, and provided with inlet openings 15, and at least one outlet opening 16.

In the present embodiment the part 12, is formed of sheet metal and substantially cylindrical, the cover part 13, is also formed of sheet metal and provided with an annular flange 17, for embracing the part 12, a tapered body part 18, which is upset to provide an annular vertical wall 19, and formed oppositely to provide a depending cone 20, the large diameter of which is less than the diameter of the vertical wall 19, so that a flat portion 21, is provided between the portion 20, and the wall 19, that may be perforated to provide a suitable number of the inlet open-

ings 15. The total area of these openings 15, should exceed the capacity of the outlet 16. The tip of the cone portion 20, is cut away or removed to provide a jet opening 22. The flange 17, is preferably welded or otherwise permanently secured to the part 12.

The bottom closure or cover part 14, is also preferably formed of sheet metal and to engage over an end 23, of the part 12. A bead 24, is formed in the part 14, to limit the relative axial movement of these parts and a bayonet connection between these parts indicated at 25, provides a means of removably attaching the parts together. The part 14, provides a dust or particle receiving chamber 26, which will be later described, and a discharge outlet 27. A hinged closure plate 28, having a hinged connection with the part 14, at 29, may also be provided to facilitate removal of accumulations from fluids cleaned and this plate may be held in closed position in any suitable manner, such as by means of a counter-weight 30. Obviously these parts may be formed otherwise and of any suitable material.

It is an object of this invention to concentrate solid particles and the like carried in suspension in fluid such as air, within the fluid and to accomplish this the fluid carrying solid particles and the like is directed along convergent lines or toward a common center or apex and the direction of fluid flow is changed, preferably just before the apex is reached, and so that the apex is located substantially at the center of a central fluid channel. The directing means in the present embodiment is provided by a member 40, having an annular flange 41, adapted to engage tightly against the wall 19, of the part 13, and embrace the inlet openings 15. The member 40, is shaped substantially in the form of a depending frustrate cone having a tapering wall portion 42, spaced from the cone 20, to provide a convergent fluid channel 43, of suitable capacity and terminating in a cylindrical portion 44, within the confines of which is located the normal apex of the convergent fluid channel 43.

It is another object of the invention to remove the fluid from the concentrated col-

lected or condensed solid particles without materially disturbing the movement of the solid particles and to remove the fluid gradually and equally in opposite directions.

- 5 To accomplish this I have shown a member or device 45, similar in form to the member 40, and oppositely disposed having an annular collar portion 46, adapted to embrace the portion 44, of the member 40, a conical portion 47, extending therefrom and terminating in an annular flange 48, spaced lug portions 49 of which are formed laterally to provide seats for an annular screen member 50. The member 45, is of less diameter than the 10 body part 12, so that a fluid passage of a relatively large capacity is provided about the periphery of the member 45, and between this part and part 12. The screen member 50, which seats against the lugs 49, of the member 20 45, and a bead 51, formed in the part 12, provides a stop or dam for a filtering mass 52, which is or may be used when fine and dust like particles are to be separated from fluid.

The filtering mass 52, is preferably formed 25 of a loosely packed fibrous material such as hair or stranded metals and is preferably supported in the lower end of the body part 12, by cross rods 53, having bearings in depending lugs 54, formed on the part 12, and 30 spaced inwardly therefrom. An outwardly curved or expanding collar 55, of pervious or screen material controls the inner contour or form of the filtering mass and this collar is preferably formed to embrace the portion 35 44, of the member 40, and to expand in increasing proportion as the distance from the portion 44 increases so as to avoid obstructing many particles having a tendency to follow the fluid into the filter mass and not to interfere with their movement into the quiescent 40 collecting chamber 26.

While as above mentioned the device is adapted to separate solids from other fluids the description of its operation will be directed to air and solids such as dust, sand, grit and the like. Extracting air through the tube 56 starts operation. Air enters the inlet openings 15 and is directed convergently through the channel 43. The path of movement of the air is changed in the tubular portion 44, and the inertia of the solid particles carries them to the center of the air column or central fluid channel 57. The jet opening 22, which is relatively small tends to shift 55 the apex of the convergent channel downwardly in proportion to the rate of fluid flow to accelerate movement of the particles, and to prevent many particles from being carried completely across the apex or central 60 channel 57, under maximum working condition. The length or internal area of the collar 55, is substantially equal to or greater than the density or obstructing capacity of the filter mass 52, and the air carrying the concentrated solid particles is directed down-

wardly through the collar 55, and toward the chamber 26. The relative shapes of the parts are such as to effect a gradual expansion of the air away from the solid particles and this effect is made more uniform by the 70 obstruction offered by the filtering mass 52. Since the removal of the air from the central channel 57, is gradual and uniform or equal in at least two directions or all directions, the movement of the solid particles into the 75 chamber 26, is not materially interrupted. When the device is operated in a perpendicular position this movement of the particles is aided by gravity. It will be noted that as the air is withdrawn or removed laterally at 80 least some of the solid particles will tend to follow the air and consequently follow a curved path, and that the contour of the part or collar 55, is such as to avoid interference with these particles so that their movement into the chamber 26, will be uninterrupted and so that the device will not become congested. Due to the arrangement of the parts the movement of the air through the filter mass is substantially horizontal and relatively slow and any fine particles carried into the mass are moved from the path of the fluid by obstruction until they precipitate from the bottom of the filter mass and into the chamber 26. Where it is essential to remove exceedingly fine substances from air the filter mass may be soaked with oil or the like. The air is drawn from the filter mass through the screen 50, and into a chamber 61, formed by the exterior of the members 40, and 45, and is removed from this chamber 61, through the tube 56.

Accumulations of particles or materials may be periodically removed through the 105 cover plate 28.

It is thought that the invention and many of its attendant advantages will be understood from the foregoing description, and it will be apparent that various changes may be made in the form, construction, and arrangement of the parts without departing from the spirit and scope of the invention, or sacrificing all of its material advantages, the form hereinbefore described being merely a preferred embodiment thereof.

I claim:

1. An air cleaner comprising, a body having inlet and outlet openings, a member mounted in said body to receive fluid from the inlet opening and being substantially of the form of an inverted frustrated cone terminating in a depending cylindrical channel portion, a second member of similar form mounted in said body and embracing the depending cylindrical channel portion of said first mentioned member and spaced from the body, said members forming a central fluid channel and an outer outlet chamber communicating with the outlet in said body, a mass filter positioned in said second member, 130

and between said central channel and said outlet chamber having a central opening therein, and a bottom closure for said body arranged to provide a quiescent chamber 5 and to receive and store materials separated from fluid.

2. A fluid cleaner comprising, a body having inlet and outlet openings, fluid directing means associated therewith whereby fluid 10 entering said body is directed convergently toward a common center for concentrating solid particles carried in suspension in said fluid and expanding the fluid away from said particles, and cooperating fluid directing 15 means for shifting the common center in accordance with the rate of fluid flow.

3. A fluid cleaner comprising, a body having an inlet opening and an outlet opening, means within said body forming a Venturi 20 tube-like fluid channel leading from said inlet opening and being contracted at its medial portion, and an open-ended inverted cone-shaped member positioned within the entering end of said channel and extending from 25 the entrance thereof to a point adjacent the contracted portion, said cone-shaped member being spaced from the walls of said channel to provide a surrounding converging passage 30 for fluid and having an opening at its apex to direct a jet of fluid to the center of the convergence of the said surrounding passage.

4. A fluid cleaner comprising a body having inlet and outlet openings, an enclosed channel member, fluid conducting means associated therewith and leading into said enclosed channel members whereby fluid is directed convergently toward a common center for concentrating solid particles carried in suspension in said fluid, said channel member 40 having perforated walls extending beyond the center of convergence of the fluid and expanding outwardly toward the sides of said body for expanding the fluid away from said solid particles, and a filtering medium covering 45 and surrounding said perforated channel walls to screen the passage toward said outlet.

5. A fluid cleaner comprising a body having inlet and outlet openings, fluid conducting means associated therewith whereby fluid entering said body is directed convergently toward a common center for concentrating solid particles carried in suspension in said fluid, means forming an enclosed channel 55 surrounding the common center of fluid convergence, said channel means having perforated walls extending beyond the center of convergence of the fluid and expanding outwardly toward the sides of said body for expanding the fluid away from said solid particles, a filtering medium covering and surrounding said perforated channel walls and extending laterally therefrom to the walls of 60 said body at a point below said outlet, and 65 a cooperating fluid conducting means direct-

ing fluid toward the said center of convergence and in the direction of flow of the converging fluid for shifting the common center in accordance with the rate of fluid flow.
